TELEPHONE LINE REPEATER

Josef Kuchley, Berlin-Siemensstadt, and Walter Kusche, Berlin-Steglitz, Germany, assignors to Siemens & Halske Aktiengesellschaft, Siemensstadt, near Berlin, Germany

Application December 28, 1935, Serial No. 56,430
In Germany January 19, 1935

3 Claims. (Cl. 179—16)

The present invention relates to a circuit arrangement for the inductive repetition of direct impulses over subscribers' lines in telephone systems.

Various arrangements of this sort are already known but they possess the disadvantage that special sources of current and special transformers have to be provided at the subscribers' stations. The range of the impulses is also limited. 5 Finally, in the case of badly insulated subscribers' lines in which considerable leakage occurs between the two leads and from the individual leads to earth, as is frequently the case with rural exchanges, the known arrangements do not 10 allow of impulse sending. These disadvantages are obviated according to the invention in that the impulses transmitted over the two leads of the line are inductively transmitted to the impulse receiving relay at the incoming end of the line by means of a further repeating coil connected symmetrically between the two halves of 15 the primary winding of the speech repeating coil.

The arrangement according to the invention has the particular advantage that it allows an undistorted transmission of impulses even when 20 there is considerable leakage between the leads of the line and between the leads and earth, because the impulse relay does not respond to interruptions in the current but to current variations.

30 The attached drawing represents three embodiments of the invention. Fig. 1 is a diagrammatic circuit drawing of one form of the invention, while Figs. 2 and 3 are similar circuit drawings showing two desirable modifications.

35 Fig. 1 represents a subscriber's automatic telephone station N which is connected with an exchange over the subscriber's line TL. If a connection with another subscriber is to be set up from the subscriber's station N the receiver is 40 first removed and relay S is accordingly energized over the contact HU of the switchhook. Relay S closes both its contacts 1s and 2s and thereby connects earth to the two leads of the subscriber's line TL by way of the impulse contact ns1 and windings I and II of the choke coil B. Two parallel circuits are thus set up from 45 earth over the two leads TL of the subscriber's line, windings a1 and a3, and a2 and a4 to battery. The windings a1 and a2 are the two halves 50 of the primary winding of the speech repeating coil Tr1, which transmits the speaking currents to the secondary windings b1 and b2. Windings a3 and a4 are the two halves of the primary winding of an impulse repeating coil Tr2 over

which the impulses are transmitted inductively to the secondary windings b3 and b4 and the polarized impulse receiving relay J in series therewith. The primary windings a1 and a2 of the speech repeating coil Tr1 are connected up so 5 that they are both arranged in the same direction relative to the speaking currents traversing the speaking leads in series and consequently transmit the speaking currents to the secondary windings b1 and b2 by induction. The two windings a1 a2 of the repeater Tr1, as regards the setting impulses traversing the two leads of the line in parallel, are connected in opposite senses relative to one another. The magnetic fields produced in this repeating coil by impulses accordingly neutralize one another so that the windings do not present any inductive resistance to the 10 passage of the impulses. On the other hand the primary windings a3 and a4 of the impulse repeater Tr2 which are connected in series with the windings a1 and a2 are arranged in such a 15 manner that they are traversed in opposite senses by the speaking currents so that they do not present any inductive resistance to these currents, while they are traversed by the setting impulses 20 transmitted over the leads in parallel in the same sense, so that the impulses are inductively transmitted to the secondary windings b3 and b4 and thus to the polarized receiving relay J.

The closing of the two parallel impulse 25 circuits on removing the receiver at the subscriber's station causes the operation of the armature of the polarized relay J at the exchange which may, for example, be used for seizing the line.

On displacing the dial during dialing windings 30 I and II of the choke coil B are short-circuited by the contact ns1. When the dial returns to normal this short-circuit is removed. During the motion of the dial the impulse contact ns1 is alternatively opened and closed in the known manner. When the parallel circuits are broken the 35 impulse receiving relay J in the exchange returns its armature to normal and when these circuits are closed the armature is again attracted. Relay J transmits the setting impulses to an operating magnet which is not shown. The 40 releasing occurs when the receiver is replaced at the subscriber's station N. Relay S thereupon deenergizes and by opening its contacts 1s and 2s breaks the parallel circuits. In the exchange 45 relay J returns its armature permanently to the rest position and thereby causes the release of the connecting device in the exchange.

Fig. 2 represents a further embodiment of the invention. In this case, however, the impulse re- 50

peating coil $Tr2$ does not possess two primary windings as in Fig. 1 but only a single primary winding $a3$ which is connected to the point of symmetry between the two primary windings $a1$ 5 and $a2$ of the speech repeating coil $Tr1$. The impulses are transmitted by induction from the primary winding $a3$ as to secondary winding $b3$ and thence to the polarized impulse receiving relay J . Otherwise the switching proceedings are 10 similar to those of Fig. 1.

Fig. 3 shows an arrangement in which in contra-distinction to those of Figs. 1 and 2 which are adapted for local battery feeding, the feeding of the subscriber takes place from battery at the 15 exchange. The primary winding $a3$ of the additional impulse repeating coil $Tr2$ is connected to a point arranged symmetrically between the two primary windings of the speech repeating coil $Tr1$. The other end of the winding is connected 20 to battery. The two primary windings of the speech repeating coil are connected in the known manner through a condenser. Earth is connected between this condenser and the lower winding of the transformer. The impulses are 25 transmitted to the impulse repeating coil $Tr2$ by means of the subscriber's dial through interruptions in the loop over the subscriber's line and the subscriber's station. These are transmitted 30 by the repeater $Tr2$ to the polarized receiving relay J .

What is claimed is:

1. In a telephone line, means for transmitting impulses over the two sides of said line in parallel, a speech repeating coil having the outside ends 35 of the primary windings connected to said line, an impulse repeating coil having its primary windings connected between the inside ends of the speech repeating coil primary windings, a source of current for impulses connected to the junction 40 of the primary winding of said impulse repeating coil, and an impulse receiving relay connect-

ed to the secondary winding of said impulse repeating coil, the impulses received over said line being inductively repeated by the windings of the impulse repeating coil to the impulse relay.

2. In a telephone system, a line extending from a station to an exchange, means for transmitting speech currents over the two sides of said line in series, means for transmitting setting impulses over the two sides of said line in parallel, a repeating coil at the exchange having its primary 5 windings connected to said line cumulatively as regards speech currents and differentially as regards setting impulses, whereby only speech currents are repeated by said repeating coil, a second repeating coil at the exchange having its 10 primary windings connected to said line differentially as regards speech currents and cumulatively as regards impulses, whereby only impulses are repeated by said second repeating coil, and an 15 impulse responding relay connected in circuit 20 with the secondary windings of said second, repeating coil.

3. In a telephone system, a line extending from a station to an exchange, said line including a repeating coil at the exchange for repeating 25 speech currents, a simplex dialing circuit superimposed on said line, said circuit including the two sides of said line in parallel, two primary windings of said repeating coil in parallel, and a current source at the exchange, a second repeating 30 coil at the exchange having its primary windings included in said simplex circuit, and an impulse responding relay in circuit with the secondary windings of said second repeating coil, the 35 said first and second repeating coils being so connected to the line as to be selectively responsive to speech currents transmitted over the two sides of the line in series and impulses transmitted over said simplex circuit, respectively.
